COOLING ELEMENT

James H. McCue, Pasadena, Calif.

Application February 29, 1944, Serial No. 524,503

5 Claims. (Cl. 261—36)

My invention relates to a cooling element, one of its objects being to reduce the temperature of air which is supplied to a room or other enclosure in a highly efficient manner. Another object is to efficiently blend cool fresh air with relatively warmer air which is withdrawn from a room or other enclosure. Another object is to reduce the temperature of water which in turn may be used for any purpose desired. Another object is to provide a cooling element which presents a maximum evaporating cooling surface whereby a comparatively large surface area is created between a stream of fluid such as air and a constant supply of cooling liquid such as water. Another object is to provide a cooling element having the above advantages which will not harbor or unduly accumulate foreign and objectionable substances caused by evaporation, or which will not become foul, unsanitary or objectionable in use. Among still further objects are maximum simplicity of construction and effectiveness in use.

With these and other ends in view my invention comprises the features of construction and combination of parts hereinafter described and claimed.

In the accompanying drawings forming part of this specification, Fig. 1 is a side elevation, partly in vertical section, of an air cooler which may be of stationary or portable type and showing my improved fluid cooling element applied thereto for use; Fig. 2 is a front elevation of a portion of the air cooler showing a form of the structure illustrated in Fig. 1 and a portion of the grill or screen broken away; Fig. 3 is a front section taken approximately on the line 3—3 of Fig. 1; Fig. 4 is a rear elevation of the cooling element when removed from the outer casing B; Fig. 5 is an enlarged vertical section of a detail showing the upper portion of the cooling element; Fig. 6 is a section taken approximately on the line 6—6 of Fig. 5, showing a portion of the upper end of the cooling element; Fig. 7 is an enlarged section of another detail, showing a portion of the lower end of the cooling element; and Fig. 8 is a section taken approximately on line 8—8 of Fig. 7.

In the drawings, I have shown my improved cooling element A applied to an air cooler such as may be used for reducing the temperature of the atmosphere in a room or other enclosure, it being understood that it is equally applicable for use in other assemblies or for cooling water or other liquid. The cooling element may be a cellular structure as will be hereinafter described

and is shown mounted in a suitable enclosure or outer casing B, having an opening 10, in its forward end, through which a stream of air, either to be reduced in temperature and conditioned or used as an evaporative medium for cooling liquid is forced in intimate contact with a constant supply of water or other cooling medium, into the chamber 11 within said enclosure and is ejected by the blower C. The blower is shown mounted in said chamber by a suitable frame 12 and is driven by the pulley 13.

My improved cooling element is composed of three cellular structures, one an air ingress or rearward section D, another a middle or liquid circulating section E, and the remaining an air egress or forward section F. Each of these cellular sections is composed of vertical and lateral thin intersecting walls 14 and 15, which provide a group of any desired number of longitudinal ducts G which are of rectangular or other suitable cross sectional shape. A continuous stream of air to be conditioned is forced through said ducts into said chamber 11 by said blower as indicated by the short arrows in Figs. 1, 5 and 7. The ducts in the middle cellular section E extend longitudinally and horizontally while the connecting portions of the ducts in the ingress or rearward section extend longitudinally but incline downwardly and join at their lower ends with the rearward ends of the horizontal portions of the ducts, and the connected portions of the ducts in the egress or forward section extend longitudinally and incline upwardly from the forward ends of the horizontal portions of said ducts. A liquid dispensing trough or reservoir H is placed immediately above the middle cellular section from which water or other suitable evaporative liquid is fed downwardly by gravity through the middle section of the cooling element and the remaining unevaporated portion of the liquid is transmitted into a sump K immediately below the middle section, from which it is recirculated back into the feed reservoir by a suitable circulating pump I. The floors of the ducts of the middle section of the cooling element are connected at the foot of each alternate companion slanting end portion of the ducts in the ingress and egress cellular sections by suitable ports 16 and 17, said ports thus being staggered, that is the port 17 at the foot of one of the downwardly slanting portions of the ingress cellular section is above the port 16 at the opposite end of the horizontal duct next below. This arrangement exists throughout the cellular structure whereby liquid fed from the reservoir H is caused to traverse

the middle cellular section in an alternating course from top to bottom and longitudinally through the ducts in the liquid circulating cell section of the cooling element. Each of the ports 16 and 17 at the ends of the middle section E resembles a slot or space across the lower ends of the corresponding floors of the horizontally adjacent ducts. In other words a port is not confined individually to each duct but traverses a horizontal series of ducts on each forward and rearward end of the cellular structure, whereby the current of air produced by the blower is spread evenly and the distribution of water or other cooling medium is equalized throughout the cooling element.

The liquid traversing downwardly in an alternating path through the middle cellular section spreads in a film by capillary attraction over the surrounding surfaces of each horizontal duct, thus exposing a large surface area of liquid in contact with the currents of air passing longitudinally through and across the entire cellular structure. In effect the horizontal ducts in the middle section form valleys in which the circulation of liquid is confined while a current of air is effectively reduced in temperature and circulated by the blower, or when desired the liquid is reduced in temperature and can be drawn off and used for cooling purposes as desired. The circulation of liquid through the middle cellular section is indicated by long arrows in Figs. 1, 5 and 7.

The cellular structure occupies the entire area of the opening 10 and as shown both the opening and the cellular structure are rectangular in shape but this shape may be varied and made suitable as desired. Any desired number and cross sectional size of the individual longitudinal ducts through the cooling element to fill the space across the opening 10 may be provided, the invention permitting a relatively large number to increase the effective evaporative surface contact between the air and cooling liquid. The walls of the cells may be made out of thin metal or any other suitable material and may be protected by any suitable non-corrosive coating to prevent deterioration.

Liquid at the terminal in the lowermost ducts in the middle section is admitted into the sump K by the opening 18. The cooling liquid is distributed and fed from the reservoir H through a series of relatively small openings 19 in the inclined floor 20, (see Fig. 3), there being a suitable number of openings above the vertical groups of cellular ducts in the middle section to provide even distribution. Each port 19 is substantially V shaped and is disposed with its apex downwardly through the floor 20. All of the openings 19 are at even elevation so as to feed the liquid evenly by gravity.

The circulating pump I is shown driven by the motor J and its delivery outlet is connected with the reservoir H by the circulating pipe 21. A valved tap 22 in the circulating pipe 21, is for the purpose of delivering cold liquid to a distant point for any use desired. A suitable screen or grid 23 placed in the opening 10 back of the cooling element serves to protect the ducts from insects and other substances which may be drawn into the cooling element and impede the efficient operation of the device. The sump K is also shown provided with a suitable overflow 24 and a valved drain 25, the latter being employed to draw off and remove any undesirable condensate or sludge trapped in the sump so that a flow of

clean and sanitary liquid can be maintained through the cooler. Also a water supply float controlled valve 26 is adapted to regulate an even supply of cooling liquid in the system at all times.

It will be noted that while I have shown my improved cooling element incorporated in a unitary structure within an enclosing chamber and from which air is propelled by a blower therein, it will be understood that this arrangement of elements may be varied within the spirit of the invention and the cooling element used in an apparatus wherein an enclosing chamber of the type shown is not employed and wherein the various associated elements shown are varied and differently arranged or modified.

In accordance with the patent statutes, I have described the principles of operation of my invention together with the construction thereof which I now consider to represent the best embodiment thereof but I desire to have it understood that the structure shown is only illustrative and that the invention can be carried out by other means and applied to uses other than those above set forth within the spirit thereof and within the scope of the following claims.

I claim:

1. A cooling element, comprising, a vertical series of superimposed longitudinal ducts, each of said ducts having opposite downwardly slanting longitudinal end portions and an intermediate longitudinal portion forming a valley between said end portions, said valleys having their opposite ends alternately connected downwardly to provide an alternating current of liquid by gravity downwardly through said series of valleys, said current of liquid being confined to the valleys by said slanting end portions of the ducts, liquid dispensing means feeding downwardly and circulating back and forth through said series of valleys, a sump into which the lower end portion of said series of valleys is connected, and means for forcing evaporating fluid longitudinally into, through and upwardly from said ducts in contact with the stream of liquid traversing said valleys, for the purposes specified.

2. A cooling element, comprising, a cluster of cells arranged in a plurality of horizontally adjacent series, the members of each series having longitudinal superimposed ducts for the flow of air therethrough, each of said ducts having upwardly inclined forward and rearward ends with a valley extending between said ends, the alternate ends of said valleys being connected downwardly to provide an alternating channel for liquid from the top to the bottom of each series of ducts, the flow of liquid being confined to the valleys by said upwardly slanting ends and being exposed to evaporation by the flow of air downwardly into, longitudinally through and upwardly from said ducts to condition the air or the liquid.

3. In a temperature reducing device, a cooling element having a cluster of air conducting cells, said cells being arranged in a plurality of laterally adjacent series, the members of each series being superimposed and each cell having a horizontal duct with downwardly inclined ingress and upwardly inclined egress ends to conduct a stream of air downwardly into, horizontally through and upwardly from each duct, and the horizontal portions of said ducts having ports at alternating opposite ends to provide an alternating passage for a stream of liquid downwardly through each of said series of cells, means for feeding liquid to the upper ends of each of said series of cells, a

sump at the lower ends of said series of cells into which unevaporated liquid is received, and means for circulating liquid from said sump into said feeding means, and means for forcing air longitudinally through said cells.

4. A cooling element, comprising, a series of superimposed cells, each cell having a longitudinal air duct, said duct having a longitudinal body portion and upwardly slanting opposite ends providing a longitudinal valley between said opposite ends, the valleys of said cells having downward ports through alternating opposite ends, providing an alternating channel downwardly through said series of cells through which liquid is adapted to flow back and forth while a current of evaporating medium is conducted downwardly into, longitudinally through and upwardly from each valley.

5. In a temperature reducing device, a cooling element having a group of air conducting cells, 20 said group of cells being arranged in a plurality

5 of laterally adjacent series, the members of each series being superimposed and each cell having a horizontal duct with downwardly inclined ingress and upwardly inclined egress ends to conduct a stream of air downwardly into, horizontally through and upwardly from each duct, and the horizontal portions of said ducts having ports at alternating opposite ends to provide an alternating passage for a stream of liquid downwardly 10 through each of said series of cells, a feeder for liquid above the group of cells having an inclined floor and ducts spaced apart through said floor to provide even feed of liquid downwardly through the valleys of the cells in said group, a sump at the lower end of said group of cells into which unevaporated liquid is received, means for circulating liquid from said sump into said feeder, and means for forcing air longitudinally through said cells.

JAMES H. McCUE.
